United States Patent Office.

JOHN P. SPANGLE, OF HOPEWELL CENTRE, NEW YORK.

Letters Patent No. 63,662, dated April 9, 1867.

IMPROVED CAR-COUPLING.

The Schedule referred to in these Letters Patent and making part of the same.

TO ALL WHOM IT MAY CONCERN:

Be it known that I, JOHN P. SPANGLE, of Hopewell Centre, in the county of Ontario, and State of New York, have made new and useful improvements in Car-Couplings; and I do hereby declare the following to be a full, clear, and exact description of the same, reference being had to the accompanying drawings, which are made part of this specification, and in which—

Figure 1 is a front view.

Figure 2 is a plan or top view.

Figure 3 is a view of the under side, a portion being in section.

Figure 4 is an end view showing the catch.

Figure 5 is a vertical section on the line $x-x$, fig. 3, to show the India-rubber pad which retains the link in its proper presentation to the approaching draw-head.

The design of my invention is to provide a self-coupling arrangement for railroad cars, and the improvements consist, first, in the jointed coupling-pin lever, which admits of the horizontal motion of the pin as the draw-head strikes; second, the arrangement of the lower lever connected to the pivoted hook and draw-head at its respective ends, and operating automatically by the impingement of either the draw-head or the link.

In the drawings A is the frame of the car; B the draw-head; C D a jointed lever pivoted to the standard of L, which is attached to the body of the car; E is the coupling-pin, pivoted to and suspended from the end of the jointed lever above spoken of; F is a hook, pivoted at P to the side of the car so as to engage with the projecting handle of the lever C D when the said handle is depressed and the coupling-pin elevated ready for the coupling of the cars; G is a lever pivoted to the under side of the car at O, the lower portion of the hook F entering a slot in its outer end, while the inner end enters into engagement with the draw-head B, which latter is continually pressed outward by the spring M contained therein; K is the coupling-link, and I the inside of the draw-head; H is the spring, which elevates the handle of the lever C D when detached from the hook, and throwing down the pin E.

The operation is as follows: The coupling arrangement being in the position shown in fig. 1, the pin is raised ready for the approaching car which carries the link, as seen in the view, fig. 3, which represents the under side. By the contact of the link with the end of the recess I in the draw-head the latter is pushed back, collapsing the spring M, and by the vibration of the lever G detaching the hook F from the handle of the lever C D, which falls, the pin E coupling with the link K. It will be observed that the pin E maintains its position at the end of the lever C D, and is never entirely withdrawn from its opening in the draw-head, and as the latter moves longitudinally of the car when struck by the link or draw-head of the approaching car, the pin moves therewith by the permission of the joint, which attaches the portion D to the portion C. The link K, as will be seen by reference to fig. 3, is maintained in a horizontal position, so as to enter the open mouth of the approaching draw-head by means of the elastic pad W, of India rubber or analogous material.

Having described my invention, what I claim therein as new, and desire to secure by Letters Patent, is—

1. The jointed upper lever C D, in combination with the coupling-pin and the receding draw-head, operating substantially as described,
2. The lower lever G, in combination with the hook F, the spring M, and draw-head I, operating substantially as described.

The above specification of my improvement in car-couplings signed by me this 8d day of March, 1866.

JOHN P. SPANGLE.
